DESIGN FOR AN OCCASIONAL TABLE

Lewis Appell and Nathaniel Appell,
New York, N. Y.

Application May 28, 1946, Serial No. 130,157

Term of patent 3½ years

(Cl. D33—14)

To all whom it may concern:

Be it known that we, Lewis Appell and Nathaniel Appell, citizens of the United States, residing at New York, in the county of Bronx and State of New York, and whose post-office address is 395 East Mosholu Parkway N., Bronx, N. Y., have invented a new, original, and ornamental Design for Occasional Table, of which the following is a specification, reference being made to the accompanying drawing, forming a part thereof:

Fig. 1 is a perspective view of an occasional table, showing our new design;

Fig. 2 is a top view thereof;

Fig. 3 is a side view thereof; and

Fig. 4 is a front elevational view thereof.

We claim:

The ornamental design for occasional table, substantially as shown.

LEWIS APPELL.
NATHANIEL APPELL.
